(57) **CLAIM**

The ornamental design for a play tent sound button, as shown and described.

DESCRIPTION

FIG. 1 is a perspective view of a sound button in accordance with the new design;

FIG. 2 is a right/left side view thereof;

FIG. 3 is a front/back view thereof;

FIG. 4 is a top view thereof; and,

FIG. 5 is a bottom view thereof.

The broken lines are for the purpose of illustrating portions of the article that form no part of the claimed design.

1 Claim, 2 Drawing Sheets---
